US00D608706S

(12) **United States Design Patent**
Schmitz et al.

(10) **Patent No.:** US D608,706 S
(45) **Date of Patent:** ** Jan. 26, 2010

(54) **OUTER PORTION OF A BRAKE ROTOR**

(75) Inventors: **Johann Schmitz**, Wurmlingen (DE);
Ingo Hoffmann, Tuttlingen (DE)

(73) Assignee: **Schwäbische-Huttenwerke Automotive
GmbH & Co. KG** (DE)

(**) Term: **14 Years**

(21) Appl. No.: **29/339,618**

(22) Filed: **Jul. 2, 2009**

Related U.S. Application Data

(62) Division of application No. 29/319,666, filed on Jun.
12, 2008.
